UNITED STATES PATENT OFFICE.

JOHN O. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

DEVICE FOR GUIDING, CLEARING, AND TENSIONING YARN.

1,405,792.

Specification of Letters Patent. Patented Feb. 7, 1922.

Application filed March 11, 1921. Serial No. 451,485.

To all whom it may concern:

Be it known that I, JOHN O. MCKEAN, a citizen of the United States, and resident of Westfield, in the county of Hampden and 5 State of Massachusetts, have invented a new and useful Improvement in Devices for Guiding, Clearing, and Tensioning Yarn, of which the following is a specification.

The object of my invention is to provide 10 certain improvements in the construction, form and arrangement of the several parts of a device for guiding, tensioning and clearing yarn, whereby the life of the device is materially lengthened; in which the parts 15 which are subject to wear may be readily replaced, and in which all liability of the catching of the yarn on the device when threading the same is eliminated.

A further object is to provide a device in 20 which the yarn may be very readily threaded through the device and maintained in its proper lead therethrough.

A practical embodiment of my invention is represented in the accompanying drawings, in which,

Fig. 1 represents the device in top plan.

Fig. 2 represents the same in side elevation.

Fig. 3 represents the device in bottom 30 plan.

Fig. 4 represents the same in front elevation.

Fig. 5 represents the device in rear elevation.

Fig. 6 represents a section taken in the plane of the line VI—VI of Fig. 1.

Fig. 7 represents the removable and reversible yarn supporting grid in perspective.

The bracket is preferably a casting and 40 it comprises a resilient yoke, the lower branch of which is designated by 1 and the upper branch by 2. These two branches are provided with lateral extensions 3 and 4 respectively, forming between them a slit 5 for the passage of the yarn. The lateral extension 3 may be provided with a downwardly extended ear 6. The upper lateral extension 4 is provided with a lug 8 from which a pin 9 projects downwardly across 45 the slit 5 to serve as a guide for the yarn as it passes from the said slit.

The upper branch 2 is swung out of its normal position to vary the width of the

slit 5 without changing the parallelism of its walls, by means of an adjusting screw, 55 the shank 10 of which passes through the upper branch 2 across the yoke and into screw-threaded engagement with the lower branch 1, the head 11 of which screw is preferably countersunk in a recess 12 in the 60 upper branch 2. As the device is shown the screw is arranged to spring the upper branch 2 toward the lower branch 1 of the yoke to narrow the yarn slit, the resiliency of the yoke serving to spring the branches apart 65 to widen the slit as the screw is turned back.

The parts hereinabove described serve to act as a very effective and simple yarn clearer or slub catcher which may be readily adjusted for different sizes of yarn and yet 70 will engage bunches, slubs, knots or other enlarged portions of the yarn.

The bracket may be supported in any suitable manner on the bar 13 of the machine, as for instance by providing the lower 75 branch of the yoke with a hollow lug 14 through which the bar 13 extends, a set screw 15 being provided for securing the bracket on the bar.

An arm 16 extends laterally from the 80 closed end of the yoke from which arm project forwardly and rearwardly respectively, fingers 17 and 18, the rearwardly extending finger 18 having a hooked end 19 which serves as a guide for the yarn as it enters 85 the device.

The gravity tension device for the yarn is constructed and arranged as follows:—

A guard 20 extends rearwardly from the lateral extension 4 of the upper branch 2 90 of the bracket and overlaps on the inside of the forwardly extended finger 17, leaving a space for the threading of the yarn. A bridge 21 leads from the rear end of the guard 20 to the upper branch 2 of the yoke. 95

A pin 22 extends through the bridge 21 and projects downwardly therefrom to a point below the yarn support, to be herein-after described, which pin is frictionally held in its position so that it may be removed from the bridge when so desired. In the present instance I have shown this pin as a cotter pin, the tension of the branches of which serve to frictionally hold the pin within the bridge. A guard 23 is provided 100 on the top of the bridge 21 for preventing 105

the yarn from being caught on the head 24 of the pin 22.

The reversible and removable yarn support which forms a part of the tensioning device for the yarn comprises a U-shaped grid 25, which spans the space between the upper branch 2 of the yoke and the forwardly projecting finger 17 of the arm 16, and which is arranged parallel to the said 10 arm 16. In the present instance one branch of this skeleton support or grid is inserted through a hole in the forwardly extended finger 17 and both branches are inserted into holes in the upper branch 2 of the yoke. 15 This grid or skeleton support is removable and reversible so that when the top of the grid becomes worn by the yarn, the grid may be removed and reversed to present a new surface and when this new surface 20 comes worn, the grid may be replaced by a new grid.

The grid may be held against unintentional removal by providing a set screw 26 which can be turned into clamping engagement with one of the branches of the grid. 25

A weighted disc 27 is loosely mounted on the pin 22 and normally rests upon the grid 25. This weighted disc is prevented from being thrown off over the top of the 30 pin by the bridge 21.

To prevent the weighted disc from falling off from the pin 22, when the grid 25 is removed for reversal or renewal, I provide a fixed pin 28 which projects laterally from 35 the upper branch 2 of the yoke between and in the plane of the branches of the grid 25.

It will be seen that by guarding the head of the pin 22 of the tensioning device and by countersinking the head 11 of the adjusting screw 10 and by other refinements 40 in the bracket I am enabled to produce a device in which the liability of the yarn to catch on the same when being threaded through the device is materially reduced, 45 thus eliminating one of the difficulties in devices of this character.

It will furthermore be seen that by the provision of a skeleton support for the yarn as it passes under the weighted disc, I am 50 enabled to produce a device in which all tendency of the filling up of the device with lint, seed or other foreign matter under the weight, which would tend to render the weight ineffective, is eliminated.

It will also be seen that by the provision 55 of a removable and reversible skeleton support for the yarn as it passes through the tensioning device, I am enabled to materially increase the life of the device as a whole.

Another valuable feature of my invention lies in the fact that when the device is in use, the weight of the tensioning device is practically supported at three points, two 65 points by the yarn and the third point by

the fixed pin 28 of the yarn support, thus tending to reduce the wear on the said support.

The hooked end 19 serves as a guide for the yarn as it enters the device and also 70 serves as a guide for preventing the escape of the yarn.

The weighted disc may be readily removed for replacement or other purposes by merely withdrawing the center pin from 75 its frictional engagement with the bridge, it being observed that no additional means is required for holding the pin in its position.

The parts shown and described, but not 80 claimed herein, which relate more particularly to the yarn clearer, form the subject matter of a copending application filed by me September 16, 1920, Serial No. 410637.

It is to be understood that the pin 28 85 which is shown between the branches of the U-shaped grid, may be omitted if so desired, in which case a four point contact for the weighted disc would be provided instead of the three point contact before 90 referred to.

It is evident that various changes may be resorted to in the construction, form and arrangement of the several parts without departing from the spirit and scope of my invention; hence I do not wish to limit myself to this particular embodiment herein shown and described, but 95

What I claim is:—

1. In a tension device, a bracket, a reversible fixed yarn support carried thereby, a freely rotatable gravity operated disc arranged to coact with said yarn support, and means for leading the yarn horizontally across said support. 100

2. In a tension device, a bracket, a removable and reversible fixed yarn support carried thereby, a freely rotatable gravity operated disc arranged to coact with said yarn support, and means for leading the yarn horizontally across said support. 105

3. In a tension device, a gravity operated disc, and a removable U-shaped grid forming a skeleton yarn support arranged to coact with said disc. 110

4. In a tension device, a gravity operated disc and a removable and reversible U-shaped grid forming a skeleton yarn support arranged to coact with said disc. 115

5. In a tension device, a gravity operated disc, a removable and reversible U-shaped grid forming a skeleton yarn support arranged to coact with said disc, and means for securing the grid against unintentional removal. 120

6. In a tension device, a gravity operated disc, a removable and reversible U-shaped grid forming a skeleton yarn support arranged to coact with said disc, means for securing the grid against unintentional re- 130

- removal, and means for holding the disc in position when the grid is removed.
7. In a tension device, a gravity operated disc, a removable and reversible U-shaped grid forming a skeleton yarn support arranged to coact with said disc, means for securing the grid against unintentional removal, and a fixed pin located between the branches of the grid for holding the disc in position when the grid is removed.
8. In a tension device, a bracket, a yarn support carried thereby, said bracket having a member located over the yarn support, a pin depending from said member, and a gravity operated disc loosely mounted on said pin, arranged to coact with said yarn support.
9. In a tension device, a bracket, a yarn support carried thereby, said bracket having a member located over the yarn support, a removable pin depending from said member, and a gravity operated disc loosely mounted on said pin, arranged to coact with said yarn support.
10. In a tension device, a bracket, a yarn support carried thereby, said bracket having a member located over the yarn support, a removable split pin depending from and frictionally held by said member against unintentional removal, and a gravity operated disc loosely mounted on said pin, arranged to coact with said yarn support.
11. In a tension device, a bracket, a yarn support carried thereby, said bracket having a member located over the yarn support, a pin depending from said member, a gravity operated disc loosely mounted on said pin, arranged to coact with said yarn support, and a yarn guard for the head of said pin, uprising from said bracket member.
12. In a tension device, a bracket, a horizontally arranged removable skeleton yarn support held at both ends in the bracket, said bracket having a member located over said yarn support, a removable pin depending from said member to a point below the yarn support, and a gravity operated disc resting on said yarn support and loosely mounted on said pin.
13. In a tension device, a bracket, a horizontally arranged reversible skeleton yarn support held at both ends in the bracket, said bracket having a member located over said yarn support, a removable pin depending from said member to a point below the yarn support, and a gravity operated disc resting on said yarn support and loosely mounted on said pin.
14. In a tension device, a bracket, a horizontally arranged removable and reversible skeleton yarn support held at both ends in the bracket, said bracket having a member located over said yarn support, a removable pin depending from said member to a point below the yarn support, and a gravity operated disc resting on said yarn support, and a gravity op-
- erated disc resting on said yarn support and loosely mounted on said pin.
15. In a tension device, a gravity operated disc, a removable yarn support arranged to coact therewith, said yarn support comprising a U-shaped grid, the branches of which span the space beneath the disc, and a set screw engaging one of the branches to hold the yarn support against unintentional removal.
16. In a tension device, a gravity operated disc, a removable and reversible yarn support arranged to coact therewith, said yarn support comprising a U-shaped grid, the branches of which span the space beneath the disc, and a set screw engaging one of the branches to hold the yarn support against unintentional removal.
17. In a tension device, a gravity operated disc, a removable and reversible yarn support arranged to coact therewith, said yarn support comprising a U-shaped grid, the branches of which span the space beneath the disc, and a fixed pin serving as a support for the weight when the yarn support is removed.
18. In a tension device, a gravity operated disc, a removable and reversible yarn support arranged to coact therewith, said yarn support comprising a U-shaped grid, the branches of which span the space beneath the disc, and a fixed pin serving as a support for the weight when the yarn support is removed, said fixed pin acting with the yarn as it passes over the two branches of the yarn support as a three point support for the disc.
19. A tension device comprising an integral resilient yoke, the upper and lower branches of which have lateral extensions forming between them a slit for the passage of the yarn, means for springing one of the branches toward the other branch to narrow the slit, a yarn support carried by the upper branch, a depending pin carried by the upper branch, and a gravity operated disc loosely mounted on said pin and normally resting on said support.
20. A tension device comprising an integral resilient yoke, the upper and lower branches of which have lateral extensions forming between them a slit for the passage of the yarn, means for springing one of the branches toward the other branch to narrow the slit, said lower branch having a laterally extended arm provided with a forwardly extended finger, a U-shaped yarn support grid having one of its branches passed through the forwardly extended finger and both of its branches inserted into said upper branch, a depending pin carried by the upper branch, and a gravity operated disc loosely mounted on said pin and normally resting on said grid.
21. A tension device comprising an inte-

gral resilient yoke, the upper and lower branches of which have lateral extensions forming between them a slit for the passage of the yarn, means for springing one of the branches toward the other branch to narrow the slit, a skeleton yarn support carried by the upper branch, a depending pin

carried by the upper branch, and a gravity operated disc loosely mounted on said pin and normally resting on said support. 10

In testimony that I claim the foregoing as my invention, I have signed my name this 2nd day of March, 1921.

JOHN O. McKEAN.
